(57) CLAIM

The ornamental design for a footwear upper, as shown and described.

DESCRIPTION

FIG. 1 is a perspective view of a footwear upper embodying the new design;

FIG. 2 is a top view thereof;

FIG. 3 is a right side view thereof;

FIG. 4 is a left side view thereof;

FIG. 5 is a front view thereof; and,

FIG. 6 is a rear view thereof.

The figures show features in dash-dash broken lines that form no part of the claimed design. The dash-dash broken lines immediately adjacent the solid line portions of the design form the boundary of the claimed design, with the broken lines forming no part of the claimed design. The bold dash-dash broken lines in the figure views depict stitching, which does form a part of the claimed design.
